UNITED STATES PATENT OFFICE.

SELTON M. WETZEL, OF PORT ORCHARD, WASHINGTON.

MOTOR-VEHICLE-MOVING ATTACHMENT.

1,138,915.

Specification of Letters Patent. Patented May 11, 1915.

Application filed February 18, 1914. Serial No. 819,508.

To all whom it may concern:

Be it known that I, SELTON M. WETZEL, a citizen of the United States, residing at Port Orchard, in the county of Kitsap and State of Washington, have invented new and useful Improvements in Motor-Vehicle-Moving Attachments, of which the following is a specification.

Operators of motor vehicles frequently become stalled by one or more of the wheels dropping into a rut or depression and assistance is generally required for moving the machine.

The present invention provides means whereby the power of the vehicle may be utilized for moving the machine so as to withdraw the wheel or wheels from the rut or depression.

In accordance with this invention a rope or cable is provided, a stake being driven into the road some distance from the vehicle and having one end of such rope or cable attached thereto, and a drum fitted to one of the drive wheels is adapted to have the opposite end portion of the rope or cable passed therearound so that when the engine is started the rope will be wound upon the drum and thereby apply the power in a manner to lift the machine from the rut or depression into which it has fallen.

The invention consists in the provision of a stake of peculiar form which will obtain firm anchorage in the ground when driven therein, said stake being provided with upper and lower hitches for attachment of the rope or cable thereto.

The invention further consists of a drum of peculiar form which is adapted to be fitted to the hub of one of the drive wheels and secured to the spokes thereof, said drum being in the nature of a hub cap upon which a portion of the rope or cable is adapted to be wound and thereby lift the machine from the depression into which it has dropped.

The invention also further consists of the novel features, details of construction and combination of parts, which hereinafter will be more particularly set forth, illustrated and claimed.

In the drawings hereto attached Figure 1 is a side view showing the application of the invention for moving a motor vehicle which has become stalled upon the road by dropping into a rut or depression. Fig. 2 is a detail view of the stake. Fig. 3 is a horizontal section on the line $w-w$ of Fig. 2.

Fig. 4 is a vertical section on the line $y-y$ of Fig. 2. Fig. 5 is a detail view of the drum. Fig. 6 is a sectional view of the drum and wheel to which the same is attached. Fig. 7 is a sectional view on the line $z-z$ of Fig. 6 showing more clearly the means for holding the wings of the drum against the sides of the spokes of the wheel.

Corresponding and like parts are referred to in the following description, and indicated in all the views of the drawings, by the same reference characters.

The stake consists of a blade 1 having two legs 2 and a stem 3, the legs 2 being tapered toward their extremities to facilitate the driving of the stake into the ground to obtain a firm anchorage for securing the end of the rope or cable 4. Ribs 5 are formed upon the rear side of the blade 1 and serve to stiffen and strengthen the stake as well as to enable the blade to be made comparatively thin and light. The ribs 5 extend along the rear side of the legs 2 and taper toward their lower ends which merge into the plane of the legs so as not to offer any material obstruction to the entrance of such legs into the ground when driving the stake. An upper hitch 6 and a lower hitch 7 are attached to the stake each being of like formation and consisting of a cross bar 8 and a draft piece 6 or 7 projecting from the cross bar. The lower hitch 7 has its draft piece arranged in the crotch formed between the legs 2 and the cross bar 8 is fitted in openings formed in the ribs 5. The hitch 6 passes through an opening 9 formed in the upper portion of the blade 1 and its cross bar is fitted in inclined slots 10 formed in the upper ends of the ribs 5. When the surface of the road is soft thereby enabling the stake to be driven deep the rope or cable 4 is attached to the upper hitch 6 but when the road is comparatively hard and firm so as not to admit of driving the stake to a great depth therein the rope or cable is attached to the lower hitch 7. The stem 3 forms convenient means for handling the stake and also for delivering the blows thereon for driving the stake into the ground.

The drum 11 is provided at one end with a plate or disk 12 which is formed at its outer edge with extensions 13 which are clamped to the spokes of the drive wheel 14 of the motor vehicle as shown. Portions are partly cut from the plate or disk 12 and are bent outward to form wings 15 which are adapted to

come between the spokes to sustain the strain as well as to assist materially in retaining the drum in position. A brace 16 of the turnbuckle variety is placed between adjacent wings 15 and serves to press such wings apart and against the opposing sides of the spokes. When the drum is in place it alines with the hub of the wheel and constitutes an extension thereof. In the preferable construction the drum 11 is hollow so as to slip over the outer end of the hub of the wheel 14.

The drum, stake and rope or cable are carried as accessories on a motor vehicle, and in an emergency the drum is attached to one of the drive wheels and the stake is driven into the ground some distance in advance of the vehicle. The rope or cable is attached to one or other of the hitches 6 or 7 and the opposite end portions of such rope or cable is passed around the drum 11, the end being held in the hands and drawn upon to cause the part of the rope passing about the drum to bind the same with sufficient friction to cause a forward pull upon the vehicle when the drive wheel is operated by starting the engine. After the parts have been adjusted in the manner stated and as illustrated in Fig. 1, the engine is started and the rope or cable is wound upon the drum 11 thereby lifting or pulling the vehicle out of the rut or depression. Should it become necessary the operation may be effected by stages that is the stake may be removed and driven into a new place and the rope or cable may from time to time be moved upon the drum when readjusting the parts preliminary to the next state for advancing the vehicle and drawing the same out of the rut or depression.

From the foregoing description, taken in connection with the accompanying drawings, the advantages of the construction and

of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

Having thus described the invention what is claimed as new, is—

1. A drum to be fitted to the drive wheel of a motor vehicle, such drum having a plate at one end formed with lateral wings to come between adjacent spokes of the drive wheel and means for pressing such wings against the opposing sides of the spokes.

2. A drum to be fitted to the drive wheel of a motor vehicle, such drum having a plate cut at a plurality of points, the cut-out portions of the plate being bent outwardly to provide wings, and means for pressing such wings against the opposing sides of the spokes.

3. A drum to be fitted to the drive wheel of a motor vehicle, such drum having a plate cut at a plurality of points, the cut-out portions of the plate being bent outwardly to provide wings, the upper edge of the plate at a plurality of points being formed to provide means whereby the plate may be permanently secured to and exteriorly of the spokes of the wheel, and means for pressing such wings against the opposing sides of the spokes.

In testimony whereof I affix my signature in presence of two witnesses.

SELTON M. WETZEL.
